UNITED STATES PATENT OFFICE.

ADOLPH A. GAZDA, OF WILKINSBURG, PENNSYLVANIA, ASSIGNOR TO WESTINGHOUSE ELECTRIC AND MANUFACTURING COMPANY, A CORPORATION OF PENNSYLVANIA.

MOTOR-CONTROL SYSTEM.

1,354,180.

Specification of Letters Patent. Patented Sept. 28, 1920.

Application filed September 30, 1916. Serial No. 123,068.

To all whom it may concern:

Be it known that I, ADOLPH A. GAZDA, a citizen of the United States, and a resident of Wilkinsburg, in the county of Allegheny and State of Pennsylvania, have invented a new and useful Improvement in Motor-Control Systems, of which the following is a specification.

My invention relates to motor-control systems, and particularly to such systems as are employed in connection with planers or similar machines requiring frequent stops and reversals of the driving mechanism.

My invention has for its object to provide a simple and efficient means for controlling the circuits of electric motors whereby they may be quickly brought to rest and automatically accelerated for operation in the opposite direction.

20 A control system arranged in accordance with my invention comprises an electromagnetically operable switch that is controlled in accordance with the counter-electromotive force of an electric motor to complete a shunt circuit for the starting resistor of the motor. The motor circuit is controlled by two electromagnetically operable line switches which are provided with back contact members for completing a dynamic 25 braking circuit for the motor when the switches are opened. The line switches are electrically interlocked in such manner that it is impossible to close one of them when the other occupies its closed position.

30 It is desirable that the switch for controlling the starting resistor be opened before the line switch corresponding to the direction of rotation of the motor is opened. This result is accomplished by the electrical 35 interlocking of the switches mentioned above in such manner that the opening of the switch for controlling the starting resistor effects the opening of the line switch that is closed.

40 My invention will be described in connection with the accompanying drawing in which the single figure is a diagrammatic view of circuits and apparatus embodying my invention.

45 Line conductors 1 and 2, which may be connected to any suitable source of direct current, supply energy to an electric motor having an armature winding 3 and a shunt field-magnet winding 4. A starting resistor 5, which is in series with the motor, is con-

trolled by an electromagnetically operable switch 6 which has an actuating coil 7 that is connected across the terminals of the motor. A relay 8, which is mechanically connected to the switch 6, is respectively 60 opened and closed when the switch 6 occupies similar positions.

The main circuit of the motor is completed for rotation in opposite directions by line switches 9 and 10 that are respectively provided with actuating coils 11 and 12. The switches 9 and 10 are mechanically connected to relays 13 and 14, respectively, which are opened and closed when the respective switches occupy their corresponding positions. The operation of the motor is controlled by push buttons 15, 16 and 17 which produce effects that are indicated by suitable legends placed adjacent to the switches.

It may be assumed that the motor is stationary and that the various switches occupy their respective illustrated or inoperative positions. To start the motor in the forward direction, the push button 15 is actuated to complete a circuit which extends 75 from line conductor 1 through actuating coil 11, push button 15 and back contact members of switch 10 to line conductor 2.

The coil 11 is energized to close switch 9 and thus complete the main circuit of the 80 motor for operation in the forward direction. This circuit extends from line conductor 1 through switch 9, armature 3, starting resistor 5 and back contact members of switch 10 to line conductor 2. When the 85 speed of the motor is such that its counter-electromotive force reaches a predetermined value, the coil 7 is energized to close switch 6 and thus complete a shunt circuit for the 90 starting resistor 5 to further accelerate the 95 motor.

The closing of relay 8 establishes a holding circuit for the coil 11 which comprises relays 13 and 8. The push button 15 may be released at any time after the closing of 100 the switch 6. The switch 10 cannot be closed by the actuation of the push button switch 16, by reason of the fact that the switch 9, in closing, creates a gap in the circuit of the push-button 16, traced below, at the back 105 contact members of the switch 9. Independently of this circumstance, however, it would be impossible to effect the closing of the switch 10 when the switch 9 is closed for the reason that the closing of the switch 9 110

establishes a short circuit for the push-button 16 and the coil 12 which extends from one terminal of the switch 9, through the conductor 18, the coil 12 and the push-button 5 ton 16 to the other terminal of the switch 9.

To stop the motor, the push button switch 17 is actuated to open the circuit of coil 7. The switch 6 then opens to insert the resistor 5 in series with the motor armature. The 10 opening of relay 8 breaks the circuit of actuating coil 11 and the switch 9 opens the main circuit of the motor.

The opening of switch 9 operates to establish a dynamic braking circuit for the 15 motor which extends from one terminal of the motor armature through the back contact members of switch 9, back contact members of switch 10 and resistor 5 to the other terminal of the motor armature. The 20 motor is thus quickly brought to rest.

To start the motor in the reverse direction, the push button switch 16 is closed to complete a circuit for the actuating coil 12 which extends from line conductor 1 25 through actuating coil 12, push button switch 16 and back contact members of switch 9 to line conductor 2. The switch 10 closes to complete the main circuit of the motor for operation in the reverse direction. 30 This circuit extends from line conductor 1 through switch 10, starting resistor 5, armature 3 and back contact members of switch 9 to line conductor 2.

The switch 6 completes a shunt circuit for 35 the resistor 5 in the manner described above, in connection with the forward rotation of the motor. A holding circuit for the coil 12 is established by the relay 8 upon the closing of switch 6. The relay 8 thus controls the position of switch 10 and it is impossible for the latter to be opened before the switch 6 has opened to insert the resistor 5 in circuit with the motor armature.

When the switch 10 is in its closed position, the push button switch 15 is ineffective to close switch 9 because the circuit, above traced, of the push-button 15 is open at the back contact members of the switch 10. Even if this were not so, however, it would 50 not be possible to close the switch 9 because its actuating coil 11 and the push-button switch 15 become short-circuited upon the closing of the switch 10, as may be seen by tracing the circuit from one terminal of the 55 switch 10, in its closed position, through the actuating coil 11 and the push-button switch 15, to the other terminal.

In the arrangement described above, an 60 electric motor may be caused to operate in either direction upon the closing of the corresponding control switch. The closing of one line switch or reversing switch automatically prevents the closing of the other switch. The line switches are so interlocked 65 with an accelerating switch that the several

switches must open in a predetermined sequence.

While I have shown and described my invention as embodying a plurality of push buttons for controlling the circuits of the 70 motor, it will be obvious that any other suitable form of controlling device may be substituted therefor. Such changes may be made without departing from the spirit of my invention as fall within the scope of the 75 appended claims.

I claim as my invention:

1. In a motor-control system, the combination with an electric motor, of a switch adapted to be closed to start said motor and 80 having an actuating coil, an accelerating switch, means for temporarily closing the circuit of said coil, and means operatively connected to said accelerating switch for maintaining the circuit of said coil energized. 85

2. In a motor-control system, the combination with an electric motor, a pair of reversing switches and an accelerating switch therefor, and actuating coils for said 90 switches, of relays operatively connected to said switches for completing a holding circuit for the actuating coil of one of said reversing switches upon the closing of the latter and of said accelerating switch. 95

3. In a motor-control system, the combination with an electric motor, a pair of reversing switches and an accelerating switch therefor, and actuating coils for said switches, of relays operatively connected to 100 said switches for completing a holding circuit for the actuating coil of one of said reversing switches upon the closing of the latter and of said accelerating switch, and means for effecting the opening of said accelerating switch to open said holding circuit. 105

4. In a motor-control system, the combination with an electric motor and a pair of reversing switches therefor having actuating coils, of an accelerating switch, means for energizing said coils, and an interlocking device operatively connected to each of said switches, the interlocking devices connected to said accelerating switch and to one of said reversing switches being series connected in circuit with the coil of said one reversing switch to maintain said coil energized. 110 115

5. In a motor-control system, the combination with an electric motor, a pair of reversing switches and an accelerating switch, of controlling means for effecting the closing of said reversing switches and means controlled by said accelerating switch for shunting said controlling means and for 125 maintaining the closure of one of said reversing switches, said means controlled by said accelerating switch causing the opening of said reversing switch when said accelerating switch is open. 130

6. In a motor-control system, the combination with an electric motor, a pair of reversing switches and an accelerating switch, of controlling means for effecting the closing of said reversing switches and means connected to said accelerating switch for creating a short-circuit for said controlling

means and for maintaining the closure of one of said reversing switches until said accelerating switch is open.

10

In testimony whereof, I have hereunto subscribed my name this 26th day of Sept. 1916.

ADOLPH A. GAZDA.
